UNITED STATES PATENT OFFICE.

CHARLES S. FISCHER, OF NEW YORK, N. Y.

UPRIGHT-PIANO-FORTE ACTION-FRAME.

SPECIFICATION forming part of Letters Patent No. 224,003, dated February 8, 1880.

Application filed November 20, 1879.

To all whom it may concern:

Be it known that I, CHARLES S. FISCHER, of the city, county, and State of New York, have invented a new and Improved Upright-Piano-Forte Frame, of which the following is a specification.

My invention relates to improvements in the manner of connecting the action-frame of upright pianos with the back and main frame; and the object of the improvements is to prevent derangement of the action-frame by the shrinkage and swelling of the wood, and from the jarring to which the instruments are subjected; also, to facilitate the removal and re-placement of the action-frame.

The invention consists in fixing the screws which connect the action-frame to the wrest in the back of the case, instead of in the wrest-plank, as heretofore.

The invention consists, secondly, in providing the end standards with L-shaped slots for the reception of pivots and bracing-pins that allow perfect freedom of oscillating movement to the action-frame, but prevent vertical movement when in position for use.

In the accompanying drawings, Figure 1 is a front elevation of an upright-piano action-frame provided with my improvements. Fig. 2 is a vertical transverse section of the same, taken on line *c c* of Fig. 1; and Fig. 3 is a vertical transverse section of a modification.

Referring to the drawings, *A* is the wrest or main frame. *B* is the back of the piano-case. *a* is the wrest-plank. *b* is the bottom rail, and *x x* are the end blocks, to which the action-frame is pivoted. *C C* are the end standards of the action-frame, and *D* represents the intermediate standards. *d* is the hammer-rail.

The parts *C D d* constitute the action-frame. *E* represents the screws which connect the action-frame with the wrest.

Heretofore those screws have been secured directly in the wrest-plank; but on account of their shortness in that construction they became loose in a short time, and the swelling and shrinkage of the wood likewise affected them and deranged the proper adjustment of the action.

In my invention a hole, *e*, is bored through the wrest-plank *a* and wrest *A* for each of

the screws *E*, preferably larger in diameter than said screws, and concentric to said hole *e* a threaded hole, *f*, is made through the back *B*. A nut, *g*, is inserted in the hole *e*, and is placed against the back *B*. The screw *E* is now passed through hole *e*, and screwed through nut *g* until its end protrudes through the back *B*, and on the outer end is placed another working nut, *h*, which is screwed up tightly against the back *B*, as in Fig. 2. In this way the screws *E* are firmly and securely connected with the back *B*, and they are thereby made altogether independent of the condition of the wrest and wrest-plank. At the same time said screws are easily removed when necessary for any purpose and adjusted in the bearings.

In Fig. 3 a modification of the above-described invention is shown. The nuts *g h* are dispensed with, and in place thereof the holes *f* through back *B* are screw-threaded, and the screws *E* are screwed into said holes.

The tapering or rounded lower ends of the intermediate standards, *D*, are set into blocks *F*, that are affixed to the bottom rail, *b*. The lower ends of the end standards, *C*, are provided with an L-shaped slot, *i*, as shown.

In each of the end blocks, *x*, are secured two pins, *k* and *k'*, which enter into the L-shaped slots *i* of standards *C*, and they are at such a distance apart in a vertical line that *k* is against the upper end of said slot, and *k'* is against the lower end and in line with the horizontal outlet thereof. This arrangement of the pins *k k'* prevents any vertical movement of the action-frame so long as the oscillating ends of the standards are in connection with the screws *E*. If it is desired to remove the action-frame, the upper ends of the standards are disconnected from the screws *E*, to which they are held by nuts *m*, and the frame is turned to a horizontal position on the pins *k*, and may then be easily lifted off. To replace the frame it is held in a horizontal position, and the pins *k k'* are passed into the L-shaped slots *i*, and the frame is then swung to a vertical position to connect with the screws *E*.

It will be perceived that the pins *k'* serve to brace the action-frame and prevent its vertical play; but they do not prevent said frame from swinging on the pivots *k*.

I claim—

1. As an improvement in upright-piano frames, the wrest A and wrest-plank *a*, provided with the apertures *e*, in combination 5 with screws E and frame C D, substantially as described.
2. The screws E, held by the back B, in combination with the wrest A and wrest-plank *a*, which are provided with the holes *e*, and with 10 the standards C D and nuts *m* of the action-frame, substantially as described.
3. The end standards, C C, provided with

L-shaped slots *i*, in combination with the pivots *k* and pins *k'*, as and for the purpose described.

4. The back B, holding the screws E, in combination with the perforated wrest or frame A and perforated wrest-plank *a*, the apertures being larger than the diameters of said screws, substantially as herein shown and described. 20

CHARLES S. FISCHER.
